(57) **CLAIM**

The ornamental design for a bottle, as shown and described.

DESCRIPTION

FIG. 1 is a top, front, right side perspective view of a bottle showing my new design, with windows on the rounded shoulder portion of the bottle being transparent;

FIG. 2 is a left side elevational view of the bottle of FIG. 1;

FIG. 3 is a rear elevational view of the bottle of FIG. 1;

FIG. 4 is a front elevational view of the bottle of FIG. 1;

FIG. 5 is a top plan view of the bottle of FIG. 1; and

FIG. 6 is a right side elevational view of the bottle of FIG. 1.

FIG. 7 is a top, front, right side perspective view of a bottle showing my new design, with windows on the rounded shoulder portion of the bottle not being transparent;

FIG. 8 is a left side elevational view of the bottle of FIG. 7;

FIG. 9 is a rear elevational view of the bottle of FIG. 7;

FIG. 10 is a front elevational view of the bottle of FIG. 7;

FIG. 11 is a top plan view of the bottle of FIG. 7; and,

FIG. 12 is a right side elevational view of the bottle of FIG. 7.
